UNITED STATES PATENT OFFICE.

NANCY M. COURT, OF LONGBEACH, CALIFORNIA.

MEANS TO PRESS CREASES IN TROUSERS.

No. 867,912.

Specification of Letters Patent.

Patented Oct. 8, 1907.

Application filed March 14, 1907. Serial No. 362,271.

To all whom it may concern:

Be it known that I, NANCY M. COURT, a citizen of the United States, residing at Longbeach, in the county of Los Angeles and State of California, have invented 5 new and useful Means to Press Creases in Trousers, of which the following is a specification.

In the drawings:—Figure 1 is a plan of my device in its open position ready for the placement therein of the trousers to be creased. Fig. 2— is a perspective view 10 of my device with a pair of trousers in place therein. Fig. 3— is an edge view thereof in its open position. Fig. 4— is an edge view of my device in its folded position for transportation or storing away. Fig. 5— is a perspective view of one of the locking clasps. 15 My device consists essentially of two strips of boards or members hinged together and adapted to be thrown into its open position as shown in Fig. 1 and into its closed position as shown in Fig. 2. The trousers 8 being folded in position to give the proper crease to the front 20 of each leg are placed into the device and the device is then clamped as shown in Fig. 2, and the locking clasps 6 are put into their closed position pressing the members of the device against the folded edges of the trousers and are left in this position any desired length

of time. The trousers are removed therefrom by throwing the clasps into the open position shown in Fig. 1. To provide means whereby the clasps may be folded into a smaller space, the clamping members may be cut in two in their centers as at 10 and the hinges 11 screwed thereinto. When made this way the clamp 30 may be easily folded into a small compass as shown in Fig. 4.

I have shown the device secured to the front of the trousers, but the same device can be used in the rear thereof. 35

Having described my invention what I claim as new and desire to secure by Letters Patent is:—

In a trousers clamp a pair of flat strips hinged together along one of their edges, each of said strips being hinged near its center so as to fold flatly on itself, and a plurality 40 of clasps pivotally secured to one of said strips and adapted to pass around the hinged edges of both of said strips and hold said strips flatly against each other.

In witness that I claim the foregoing I have hereunto subscribed my name this 6 day of March, 1907.

NANCY M. COURT.
